ICE SCORING MACHINE

Migiel J. Uline, Washington, D. C.

Application March 6, 1934, Serial No. 714,339

15 Claims. (Cl. 125—13)

This invention relates to certain new and useful improvements in ice scoring machines and more particularly to an improvement on my patent for Ice scoring machine granted May 10, 1932, No. 1,857,894, the object being to provide means for scoring the cakes of ice longitudinally at their longitudinal centers or to each side of the longitudinal center in order to increase the sections whereby the cake can be divided into a greater number of sections of equal volume, the construction being exceedingly simple whereby it can be readily shifted to longitudinally score the cake of ice at the center or to score it to each side of the center.

Another object of my invention is to provide novel means for adjusting the horizontally disposed saws on the vertically disposed arbors whereby these saws can be readily positioned on the arbor and held in that position to either form a single longitudinal score or a double longitudinal score in the sides of the cake of ice.

Another object of my invention is to provide a construction which can be readily used in connection with an ice scoring machine as disclosed in my above referred to patent, which is provided with feed mechanism for feeding a cake of ice into the frame so that as the cake is moved into the frame longitudinal scores can be formed in the sides of the cake and after the cake has been positioned within the frame of the machine, transverse scores can be formed in the sides of the cake in order to divide the cake into a plurality of sections of equal volume.

While I have shown and described my improved construction of longitudinal scoring means applied to a machine as disclosed in my patent granted May 10, 1932, No. 1,857,894, I wish it to be clearly understood that my invention is capable of being used with various types of scoring machines which are provided with means for forming longitudinal scores in the opposing sides of the cake of ice as it passes through the machine and therefore I do not wish to limit myself to the use of my improved construction of longitudinal scoring means to any particular type of machine as I am aware that it can be readily used in connection, as for example, with a Uline ice scoring machine as now being manufactured.

Other and further objects and advantages of the invention will be hereinafter set forth and the novel features thereof defined by the appended claims.

In the drawings,
Figure 1 is a side elevation of an ice scoring

machine as disclosed in my Patent No. 1,857,894, dated May 10, 1932, showing the application of my improved construction of longitudinal scoring means thereto;

Figure 2 is a transverse cross section through the machine showing the means for adjusting the horizontally disposed saws on the vertical arbors for forming a single or a double score in the sides of the cake of ice;

Figure 3 is a similar transverse section showing the manner of mounting the transverse scoring means and adjusting the same, the same being illustrated to show the driving means for the vertical arbors of the longitudinal scoring means;

Figure 4 is a detail top plan view, partly in section, showing the driving means employed for driving the horizontally disposed saw arbors and the vertically disposed saw arbors;

Figure 5 is an enlarged section, partly in elevation, showing one of the vertical saw arbors in the position to score a cake of ice longitudinally at the center line of the cake;

Figure 6 is a vertical section, partly in elevation, showing the saws adjusted to each side of the longitudinal center in order to form parallel scores longitudinally of the cake;

Figure 7 is a section taken on line 7—7 of Figure 5 showing the manner of splining the saws on the saw arbors; and

Figure 8 is a detail plan view of one of the scoring saws showing it formed in sections in order to allow the same to be inserted and removed from the saw arbors.

In the drawings I have illustrated in a broad way the mechanism for operating an ice scoring machine constructed in accordance with my invention using a portion of the structure disclosed in my Patent No. 1,857,894.

In the drawings 1 indicates a frame through which travels feed mechanism 2 constructed substantially the same as shown in my patent, said feed mechanism being adapted to feed a cake of ice into the frame so as to cut longitudinal scores on the sides of the cake of ice and to position the cake of ice within the frame so as to cut transverse scores on the ice.

The transverse scoring means comprises a pair of saw arbors 3 and 4 provided with a plurality of saws 5 and 6, said arbors being mounted in bearings arranged within slides 7 and 8 at one end, which slides are mounted on guide rods 9 and are connected to an endless chain 10 passing around sprocket wheels 11 and 12. The opposite ends of the arbors 3 and 4 are mounted in bear-

ings arranged in boxes 13 and 14 carried by slides 15 mounted on guide rods 16. The boxes 13 and 14 surround vertical shafts 17 and 18 on which are splined beveled gears 19 and 20, which mesh with beveled gears 21 and 22 carried respectively by the saw arbors 3 and 4 whereby these arbors will be rotated.

These boxes have a connection with an endless chain 23 working over sprocket wheels 24 and 25 so that as one arbor is moved upwardly to form a plurality of transverse scores in the side of the cake of ice, the other arbor will be moved downwardly to form a series of transverse scores in the opposite side of the cake of ice, the chains being driven by suitable driving means in connection with timing mechanism which controls the feed mechanism whereby when the cake is properly positioned after having its longitudinal scores formed in the sides of the ice, the transverse scoring arbors will be moved vertically so as to form transverse scores in the sides of the cake of ice.

The particular construction of driving means for operating the transverse scoring means forms no part of my invention and the above description is given so that the operation of my improved construction of longitudinal scoring means will be clearly understood.

The upper end of the shafts 17 and 18 are provided with beveled gears 26 and 27, which mesh with beveled gears 28 and 29 carried by a horizontal shaft 30 provided with a sprocket wheel 31 over which passes a chain 32 which passes over a sprocket 33 fixed on the drive shaft 34 of an electric motor 35 whereby the horizontally disposed arbors 3 and 4 carrying the plurality of saws for forming the transverse scoring means will be driven by an electric motor.

All of the above construction previously described is shown in my Patent No. 1,857,894, dated May 10, 1932 and forms no part of this invention per se and therefore I have only described broadly the operating means for such transverse scoring means.

Disposed in advance of the shafts 17 and 18 are vertically splined arbors 36 and 37 which are mounted in bearings 38 at their lower ends and bearings 39 at their upper ends, the upper ends carrying gears 40 which mesh with intermediate gears 41 which in turn mesh with gears 42 carried respectively by the shafts 17 and 18, whereby the vertically disposed arbors 36 and 37 will be driven from the electric motor through the shafts 17 and 18, gears 40, 41 and 42.

The arbors 36 and 37 are formed exactly alike and the description of one will be sufficient for both, each arbor being formed with a plurality of grooves 43 which receive tongues 44 of sectional hubs 45 and 46, which are provided with scoring saws 47 and 48. The hubs 45 and 46 are provided with collars 49 and 50 through which the bolts 49a pass for clamping the saws 47 and 48 in position between the sections and the sections together whereby the saws can be readily inserted and removed.

Fixed on each arbor adjacent its lower end is a stop 51 which is surrounded by a sleeve 52 carried by the hub 46 below the saw 48. The hub 46 above the saw 48 carries a sleeve 53 having an annular outwardly extending flange 54 at its upper end which cooperates with an annular flange 55 formed on the lower end of a sleeve 56 which is carried by the hub 45 whereby a telescopic connection is formed between the two saws. A second stop 57 is carried by the arbor

above the saw 48 and is adapted to be engaged by the hub 45 when moved down into position shown in Figure 6 at the same time the hub 46 engages the stop 51 whereby the two horizontally disposed scoring saws are in position to form parallel scores to each side of the longitudinal center of the cakes of ice.

The upper hub 45 is provided with a collar 58 having an internal flange 59 at its upper end engaging an annular flange 60 on a sleeve 61 loosely mounted on the arbor and provided with a rack 62 which engages a gear 63 carried by a shaft 64 which is provided with a crank arm 65 having a spring pressed pin 66 which is adapted to engage an opening 67 formed in a plate 68 carried by the frame 1 of the machine whereby upon rotation of the shaft 64 the two saws 47 and 48 can be raised and lowered in position so as to form a single score or a double score in the side of the cake of ice.

In the drawings I have failed to show a ball bearing connection between the sleeve 61 and collar 58 and I wish to reserve the right to use a ball bearing at the junction of these two members.

In the operation of an ice scoring machine constructed in accordance with my invention when it is desired to form a single score longitudinally in the sides of the cake of ice in the center of the cake, the saws are adjusted in the position shown in Figure 5 with the upper saw 47 approximately one inch above the top of the cake of ice. As the cake of ice is moved by the feeding mechanism of the machine into the machine it passes the saws 48 which form longitudinal scores on the sides of the cake of ice along the center line. The movement of the cake is then arrested by the feeding mechanism and through suitable timing mechanism as fully disclosed in my patent, the transverse scoring means are set in operation so that the arbors 3 and 4 travel up and down the sides of the cake of ice or in other words, as one arbor goes up, the other goes down so as to form transverse scores in the sides of the ice. This divides the cake of ice into sections of equal volume.

When it is desired to increase the number of sections, the crank 65 is operated so as to lower the upper saw 47 and the lower saw 48 into the position shown in Figure 6 and as the cake of ice is moved by the feeding mechanism into the machine, a pair of scores are formed in the side of cake of ice to each side of its longitudinal center whereby the cake will be divided into a greater number of sections of equal volume.

This provides means for converting an ordinary construction of ice scoring machine which is only capable of forming a cake of ice with a certain number of sections into a machine which is capable of forming a cake of ice into a greater number of sections by merely operating a crank, the construction being such that the saws are readily adjusted and held in adjusted position so as to form the desired number of scores in the sides of the cake of ice without any danger of these saws moving when in operation out of their adjusted position.

The scoring saws are preferably formed in sections as shown in Figure 8 in order to allow these saws to be placed in position upon the arbors or removed therefrom without dismantling the machine.

While in the drawings I have illustrated certain details of construction in forming the vertical saw arbors for forming the longitudinal

5 scores and the particular manner of mounting the same and adjusting the same, I wish it to be clearly understood that I do not wish to limit myself to any particular means for mounting and 10 adjusting these horizontal saws on the vertically disposed saw arbors for forming the longitudinal scores as my invention consists broadly in providing an ice scoring machine with a pair of arbors one arranged to each side of a frame 15 through which a cake of ice is adapted to pass, each arbor having more than one horizontally disposed saw slidably mounted thereon with means for adjusting said saws into position on said arbors whereby one or more of said saws 20 can be positioned to cut one or more scores in the sides of the cake of ice as it passes through the machine. While I have only shown two saws on each arbor, it is, of course, understood that these arbors can be provided with two or more 25 saws which are adjustably mounted thereon whereby a number of longitudinal scores could be formed in the sides of the cake of ice as it moves through the machine.

30 In the embodiment of my invention as herein shown, I have only illustrated two saws, one of which is always in position to form a longitudinal score on the cake of ice and the other of which is normally out of position to form a longitudinal score in the cake of ice, said saws being capable of being adjusted on the respective arbors whereby they can be brought into contact with the cake of ice independently or simultaneously for increasing the number of sections of equal volume.

35 From the foregoing description it will be apparent that my improved construction of longitudinal scoring means is capable of being used with other types of scoring machines than what is herein shown, therefore I do not wish to limit myself to the use of any particular construction 40 of scoring means so long as means is provided for moving a cake of ice past the scoring saws.

45 The construction herein shown and described provides novel means for positioning the saws on the arbors and holding said saws in adjusted position and while I have shown certain details of construction, I am aware that various changes can be made without departing from the spirit 50 of my invention.

55 The plate 68 is provided with two openings 67 to receive the pin 66 of the crank 65 when in its adjusted positions, whereby when the crank is operated to position the saw 48 at the center of the cake of ice, the pin 66 will enter one opening 67 and hold the saw 48 at the center of the cake of ice and the saw 47 above the cake of ice. When the crank is adjusted to lower the saws 47 and 48 into the position shown in Figure 6 so as 60 to cut parallel scores in the cake of ice to each side of the center, the pin 66 of the crank will enter the other opening of the plate 68 and hold these two saws in this position whereby the saws are locked in their adjusted position to prevent 65 any danger of their being displaced when in operation.

What I claim is:

70 1. In an ice scoring machine, a revolving saw arbor, saws feathered on said arbor, a sliding connection between said saws and stops fixed on said arbor for positioning said saws thereon.

2. In an ice scoring machine, a revolving saw arbor, hubs feathered on said arbor, saws carried by said hubs, a sliding connection between said 75 hubs, means for moving said hubs longitudinally

on said arbor and stops for positioning said saws on said arbor.

3. In an ice scoring machine, a revolving saw arbor, hubs feathered on said arbor, saws adjustably mounted on said hubs, a telescopic connection between said hubs and stops arranged on said arbor for positioning said hubs thereon. 5

4. An ice scoring machine having means for forming longitudinal and transverse scores in a cake of ice, said longitudinal scoring means comprising saw arbors having saws slidably mounted thereon, spacing means disposed between said saws and means for adjusting one of said saws for positioning said saws on said arbor for forming one or more scores in said cake of ice. 10 15

5. An ice scoring machine comprising a frame, means for supporting and feeding a cake of ice through said frame, a saw arbor arranged to each side of said feeding means, hubs feathered on said arbors, saws fixed on said hubs, sleeves carried by said hubs having a telescopic connection with one another, stops arranged on said arbors adapted to engage said hubs for positioning said hubs on said arbors and means for raising and lowering said hubs. 20 25

6. An ice scoring machine comprising a frame, means for supporting and feeding a cake of ice through said frame, a saw arbor arranged to each side of said feeding means, hubs feathered on said arbors, saws fixed on said hubs, sleeves 30 carried by said hubs having a telescopic connection with one another, stops arranged on said arbors adapted to engage said hubs for positioning said hubs on said arbors, means for raising and lowering said hubs, said means comprising 35 racks and gears.

7. In an ice scoring machine, a frame having means for feeding a cake of ice therethrough, a saw arbor arranged to one side of said feeding means, hubs feathered on said arbors, saws carried by said hubs, stops fixed on said arbors for positioning said hubs thereon, sleeves carried by said hubs having a sliding connection with one another, a sleeve provided with a rack connected to one of said sleeves and a crank operated gear 45 engaging said rack for moving said hubs up and down on said arbors. 42 45

8. In an ice scoring machine, a frame having means for feeding a cake of ice therethrough, means for forming transverse and longitudinal 50 scores in the sides of the cake of ice, said longitudinal scoring means comprising arbors having hubs feathered thereon provided with saws, collapsible means disposed between said saws for spacing said saws and means for raising or lowering one of said saws for positioning said saws on said arbors to form one or more longitudinal scores in the cake of ice in its movement through said frame. 55

9. In an ice scoring machine of the kind described, a frame, means for feeding a block of ice longitudinally through said frame, means for forming transverse scores in the side of said block, means for forming one or more longitudinal scores in the sides of said block, said longitudinal scoring means comprising vertically disposed arbors having horizontally disposed saws feathered thereon, collapsible means disposed between said saws for spacing said saws on said arbors and means for adjusting one of said 70 saws on said arbors for positioning said saws on said arbors for forming one or more scores in said block as said block moves through said machine. 60 65

10. In an ice scoring machine, a pair of arbors 75

between which a cake of ice is adapted to be moved, saws slidably mounted on said arbors, collapsible means for spacing said saws on said arbors and means for adjusting said saws on said arbors and holding said saws in adjusted position.

11. In an ice scoring machine, a vertically disposed arbor, a pair of hubs feathered on said arbor carrying saws, stops for positioning said hubs on said arbor and a sliding connection between said hubs for moving and holding said hubs in contact with said stops.

12. In an ice scoring machine, an arbor, hubs feathered on said arbor, a sliding connection between said hubs and means for positioning said hubs on said arbor and holding said hubs in adjusted position.

13. In an ice scoring machine, a frame, means for feeding a cake of ice through said frame, an arbor arranged to each side of said feeding means, hubs provided with saws feathered on said arbor,

sleeves having a telescopic connection connecting said hubs and means connected to one of said hubs for positioning said hubs on said arbor.

14. In an ice scoring machine, a revolvably mounted saw arbor, hubs feathered on said arbor, sleeves carried by said hubs having a telescopic connection, stops fixed on said arbor adapted to be engaged by said hubs and means for moving one of said hubs longitudinally on said arbor for positioning and holding said arbor in adjusted position.

15. An ice scoring machine of the kind described having revolvble saw arbors between which a cake of ice is adapted to be moved, horizontally disposed saws feathered on said arbors, collapsible means disposed between said saws for spacing said saws apart on said arbors and means for moving the upper saw for positioning said saws on said arbors for increasing or decreasing the distance between said saws.

MIGIEL J. ULINE.
